CLAIM

The ornamental design for a display with icon for oral-care appliance, as shown and described.

DESCRIPTION

FIG. 1 is a perspective view of a first embodiment of the display with icon for oral-care appliance;
FIG. 2 is a front view thereof;
FIG. 3 is a right-side view thereof;
FIG. 4 is a rear view thereof;
FIG. 5 is a left-side view thereof;
FIG. 6 is a top plan view thereof;
FIG. 7 is a bottom view thereof.
FIG. 8 is a perspective view of a second embodiment of the display with icon for oral-care appliance;
FIG. 9 is a front view thereof;
FIG. 10 is a right-side view thereof;

FIG. 11 is a rear view thereof;
FIG. 12 is a left-side view thereof;
FIG. 13 is a top plan view thereof;
FIG. 14 is a bottom view thereof.
FIG. 15 is a perspective view of a third embodiment of the display with icon for oral-care appliance;
FIG. 16 is a front view thereof;
FIG. 17 is a right-side view thereof;
FIG. 18 is a rear view thereof;
FIG. 19 is a left-side view thereof;
FIG. 20 is a top plan view thereof;
FIG. 21 is a bottom view thereof.

FIG. 22 is a perspective view of a fourth embodiment of the display with icon for oral-care appliance;
FIG. 23 is a front view thereof;
FIG. 24 is a right-side view thereof;
FIG. 25 is a rear view thereof;
FIG. 26 is a left-side view thereof;
FIG. 27 is a top plan view thereof; and,
FIG. 28 is a bottom view thereof.

The broken line at the periphery of the figure illustrates the display and the remaining broken lines illustrate portions of the oral-care appliance. None of the broken lines form part of the claimed design.
